(57) CLAIM

The ornamental design for a display screen or portion thereof with icon, as shown and described.

DESCRIPTION

The patent file contains at least one drawing executed in color. Copies of this patent with a color drawing will be provided by the Office upon request and payment of the necessary fee.

FIG. 1 is a front view of a display screen or portion thereof with icon showing our new design; and,

FIG. 2 is a front view of a display screen or portion thereof with icon showing an alternate embodiment of our new design.

The broken lines in the figures show a display screen or portion thereof, and form no part of the claimed design.
